(57) **CLAIM**

The ornamental design for an absorbent multiple-layer protective pad, as shown.

DESCRIPTION

FIG. 1 is a top front perspective view of an absorbent multiple-layer protective pad according to the present design;

FIG. 2 is a bottom front perspective view of the absorbent multiple-layer protective pad of FIG. 1;

FIG. 3 is a top plan view of the absorbent multiple-layer protective pad of FIG. 1;

FIG. 4 is a bottom plan view of the absorbent multiple-layer protective pad of FIG. 1;

FIG. 5 is an enlarged scale, front edge view of the absorbent multiple-layer protective pad of FIG. 1; and,

FIG. 6 is an enlarged scale, side edge view of the absorbent multiple-layer protective pad of FIG. 1.
